(57) **CLAIM**

The ornamental design for a phone case with card holder, as shown and described.

DESCRIPTION

FIG. 1 is a perspective view of a phone case with card holder showing my new design;

FIG. 2 is a perspective view thereof showing the phone case and card holder components of the design in a separated state for clarity of disclosure;

FIG. 3 is a front view thereof showing the phone case component of the design in isolation for clarity of disclosure;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front view thereof showing the card holder component of the design in isolation for clarity of disclosure;

FIG. 10 is a back view thereof;

FIG. 11 is a left side view thereof;

FIG. 12 is a right side view thereof;

FIG. 13 is a top view thereof; and,

FIG. 14 is a bottom view thereof.

For clarity of disclosure, the components of the phone case with card holder are shown in isolation in FIGS. 3–14 and separated in FIG. 2. Although the phone case with card holder, in which the claimed design is embodied, consists of a phone case component and a card holder component, the claim is directed to the overall ornamental appearance of the phone case with card holder in its entirety and does not extend to the ornamental appearance of each of the individual components in isolation.
